US00D575783S

(12) **United States Design Patent**
Hean et al.

(10) **Patent No.:** US D575,783 S
(45) **Date of Patent:** ** Aug. 26, 2008

(54) **DISPLAY DEVICE**

(75) Inventors: **Kenneth Ding Yin Hean**, Singapore (SG); **Chan Wai Lim**, Singapore (SG)

(73) Assignee: **Dell Products L.P.**, Round Rock, TX (US)

(**) Term: **14 Years**

(21) Appl. No.: **29/276,373**

(22) Filed: **Jan. 24, 2007**

(51) **LOC (8) Cl.** 14-02

(52) **U.S. Cl.** **D14/375**

(58) **Field of Classification Search** D14/371-375, D14/125-129; 345/104, 156, 168, 173, 901-905; 348/180, 184, 325, 739, 836; 248/918-924, 248/146, 121, 157, 278.1; 349/1, 2, 11, 62; 341/12; 361/680-686

See application file for complete search history.
